Primary Examiner — Janice Seeger(74) *Attorney, Agent, or Firm* — Neal, Gerber & Eisenberg LLP(57) **CLAIM**

The ornamental design for a bedding cover, as shown and described herein.

DESCRIPTION

FIG. 1 is a front top perspective view of one embodiment of a bedding cover of our new design in a resting state, that portion of the bedding cover shown in phantom is not part of the design sought to be patented and is provided for environmental purposes only.

FIG. 2 is a front top perspective view of the bedding cover of our new design illustrated in FIG. 1 in an expanded state, that

portion of the bedding cover shown in phantom is not part of the design sought to be patented and is provided for environmental purposes only.

FIG. 3 is a rear top perspective view of the bedding cover of our new design illustrated in FIG. 2.

FIG. 4 is a front bottom perspective view of the bedding cover of our new design illustrated in FIG. 2.

FIG. 5 is a rear bottom perspective view of the bedding cover of our new design illustrated in FIG. 2.

FIG. 6 is a front elevational view of the bedding cover of our new design illustrated in FIG. 2, that portion of the bedding cover shown in phantom is not part of the design sought to be patented and is provided for environmental purposes only.

FIG. 7 is a rear elevational view of the bedding cover of our new design illustrated in FIG. 2.

FIG. 8 is a left side elevational view of the bedding cover of our new design illustrated in FIG. 2, that portion of the bedding cover shown in phantom is not part of the design sought to be patented and is provided for environmental purposes only.

FIG. 9 is a right side elevational view of the bedding cover of our new design illustrated in FIG. 2, that portion of the bedding cover shown in phantom is not part of the design sought to be patented and is provided for environmental purposes only.

FIG. 10 is a top plan view of the bedding cover of our new design illustrated in FIG. 2.

FIG. 11 is a bottom plan view of the bedding cover of our new design illustrated in FIG. 2, that portion of the bedding cover shown in phantom is not part of the design sought to be patented and is provided for environmental purposes only.

FIG. 12 is a front top perspective view of another embodiment of a bedding cover of our new design in a resting state, that portion of the bedding cover shown in phantom is not part of the design sought to be patented and is provided for environmental purposes only.

FIG. 13 is a front top perspective view of the bedding cover of our new design illustrated in FIG. 12 in an expanded state, that portion of the bedding cover shown in phantom is not part of the design sought to be patented and is provided for environmental purposes only.

FIG. 14 is a rear top perspective view of the bedding cover of our new design illustrated in FIG. 13, that portion of the bedding cover shown in phantom is not part of the design sought to be patented and is provided for environmental purposes only.

FIG. 15 is a front bottom perspective view of the bedding cover of our new design illustrated in FIG. 13, that portion of the bedding cover shown in phantom is not part of the design sought to be patented and is provided for environmental purposes only.

FIG. 16 is a rear bottom perspective view of the bedding cover of our new design illustrated in FIG. 13, that portion of the bedding cover shown in phantom is not part of the design sought to be patented and is provided for environmental purposes only.

FIG. 17 is a front elevational view of the bedding cover of our new design illustrated in FIG. 13, that portion of the bedding cover shown in phantom is not part of the design sought to be patented and is provided for environmental purposes only.

FIG. 18 is a rear elevational view of the bedding cover of our new design illustrated in FIG. 13.

FIG. 19 is a left side elevational view of the bedding cover of our new design illustrated in FIG. 13, that portion of the bedding cover shown in phantom is not part of the design sought to be patented and is provided for environmental purposes only.

FIG. 20 is a right side elevational view of the bedding cover of our new design illustrated in FIG. 13, that portion of the bedding cover shown in phantom is not part of the design sought to be patented and is provided for environmental purposes only.

FIG. 21 is a top plan view of the bedding cover of our new design illustrated in FIG. 13; and,

FIG. 22 is a bottom plan view of the bedding cover of our new design illustrated in FIG. 13, that portion of the bedding cover shown in phantom is not part of the design sought to be patented and is provided for environmental purposes only.
